UNITED STATES PATENT OFFICE.

HORACE C. McCONNELL, OF ROCK ISLAND, ILLINOIS.

HARNESS-SADDLE.

SPECIFICATION forming part of Letters Patent No. 308,919, dated December 9, 1884.

Application filed April 9, 1884. (No model.)

To all whom it may concern:

Be it known that I, HORACE C. McCONNELL, of Rock Island, in the county of Rock Island and in the State of Illinois, have invented certain new and useful Improvements in Harness-Saddles; and I do hereby declare that the following is a full, clear, and exact description thereof, reference being had to the accompanying drawings, making a part of this specification, in which—

Figure 1 is a perspective view of my improved device as arranged for use. Fig. 2 is a like view of one of the jockeys, the terret-plate, and the engaging end of the yoke separated from each other. Fig. 3 is a perspective view of the lower sides of said jockey and terret-plate, and Fig. 4 is a central longitudinal section upon line $x-x$ of Fig. 1.

Letters of like name and kind refer to like parts in each of the figures.

My invention has for its object the securing of a cheaper, more convenient, and stronger connection between the yoke and jockey of a harness-saddle; and to this end it consists, principally, in a yoke having at its end a transverse hinge or pivotal bar, in combination with a jockey that is provided with a transverse bearing for said bar, and with means, substantially as shown, whereby said parts are held in engagement, substantially as and for the purpose hereinafter specified.

It consists, further, in a yoke having within each end an opening which is formed by two arms that extend downward and are connected together at their ends by a transverse bar, in combination with a jockey that is provided with a transverse bearing for said bar, and with means, substantially as shown, whereby said parts are held in engagement, substantially as and for the purpose hereinafter shown.

It consists, further, in combining with the end of a yoke a jockey which is hinged or pivoted thereto, and is provided with side flanges that extend upward beside the edges of said yoke and operate to prevent the relative lateral movement of either part, substantially as and for the purpose hereinafter shown.

It consists, finally, in the combination of the yoke, the jockey, the terret-plate, and the terret, substantially as and for the purpose hereinafter set forth.

In the accompanying drawings, A represents a yoke or tree that is of usual construction, except at its ends a , each of which is provided with an opening, a' , that is preferably semicircular at its upper end, which terminates at and is formed by means of a transverse bar, a'' , that is substantially half-round in cross-section, and within its upper side, at its longitudinal center, is provided with a half-round transverse notch or groove, a''' . The jockey B has any desired or usual form of construction of its lower end to adapt it to receive the ends of the skirts C, but at its upper end is provided within its upper face with a sunk portion, b , that is bounded at each side by a vertical flange, b' , and has such size and shape as to adapt it to receive and contain one of the ends a of the yoke A.

At the lower end of the recessed part b is provided a semicircular bearing, b'' , which is wholly below the surface of said part, and is to receive and contain the bar a'' of the yoke A. Said bearing is preferably made with several openings, as shown, for the purpose of lessening the weight of said jockey, but may, if desired, be made solid, except that at the longitudinal center of its lower side an opening, b''' , is required, for purposes hereinafter explained.

When the yoke end a is in place within the jockey B, there is placed within the opening a' a terret-plate, D, which loosely fills the same and extends over the pivotal bar a'' to the lower end of the sunk portion b . The lower face of said plate is recessed immediately over said bar, to enable the former to fit down over the latter, and is provided with a central longitudinal rib or spur, d , that fits within the notch a''' of said bar and projects into the opening b'' of said plate.

The plate D is provided with a centrally-located opening, d' , and immediately beneath the same, within the jockey B, is a similar opening, b'' , through which and through said opening d' is passed the shank e of terret E, of usual construction. A nut, F, upon the lower threaded end of said shank operates to secure said terret in place and to closely bind together said plate D and jockey B. The yoke A and jockey B, thus connected, have perfect freedom of motion to enable the saddle to adjust itself to the back of a horse, while in con-

sequence of the length of the pivotal bearing a^2 , and more especially the side flanges, b' , all independent lateral movement of either part is prevented, and great strength in such direction is secured.

The construction shown is exceedingly simple, its cost is small, and the parts may be easily and quickly connected with or disconnected from each other when desired.

Having thus fully set forth the nature and merits of my invention, what I claim as new is—

1. A yoke having within each end an opening which is formed by two arms that extend downward and are connected together at their ends by a transverse bar, in combination with a jockey that is provided with a transverse bearing for said bar, with upwardly-extending flanges between which fits the end of the yoke, and with means, substantially as shown, whereby said parts are held in engagement, substantially as and for the purpose shown.

2. In combination with the yoke provided near its end with an opening, and at its end with a pivotal bar notched in its upper face, the jockey provided with a transverse groove to receive the bar, and with an opening in its raised portion beyond the bar, the plate resting on the upper end of the jockey, and provided with a spur engaging the notch in the pivotal bar and extending into the opening

in the jockey, and the terret-screw passing through plate and jockey and holding them together, substantially as and for the purpose described.

3. In combination with the end of the yoke provided with an opening, a' , and the pivotal bar a^2 , having on its upper side a notch, a^3 , the jockey B, having the sunk portion b , the bearing b^2 for the bar, and the opening b^3 , and the plate D, fitting within the opening in yoke end, and provided with a spur which engages the notch a^3 and extends into the opening b^3 in the jockey, and with portions overlapping the bar a^2 on each side of the notch therein, substantially as and for the purpose described.

4. The yoke A, provided at its ends with the openings a' and pivotal bars a^2 , the jockeys B, having the sunk portions b , flanges b' , and bearings b^2 , the plates D, provided with the spurs d , and the terrets E, passing through said plates and jockeys, all combined to operate in the manner and for the purpose substantially as shown and described.

In testimony that I claim the foregoing I have hereunto set my hand this 20th day of March, 1884.

HORACE C. McCONNELL.
